Primary Examiner — Holly Baynham(74) *Attorney, Agent, or Firm* — Sheridan Ross P.C.(57) **CLAIM**

The ornamental design for a messenger bag, as shown and described.

DESCRIPTION

FIG. 1 is a front perspective view of a messenger bag;
FIG. 2 is a front elevation view thereof;
FIG. 3 is a rear elevation view thereof;
FIG. 4 is a right elevation view thereof;
FIG. 5 is a left elevation view thereof;
FIG. 6 is a top plan view thereof; and,
FIG. 7 is a front perspective view of a messenger bag according to an alternative embodiment of a messenger bag, the front, rear, right and left views of which appear substantially similar to FIGS. 2–5, respectively.

The broken lines showing buckles, handles and zipper are for the purposes of illustrating environment and form no part of the claimed design.
